UNITED STATES PATENT OFFICE

WALTER O. HOLT, OF PROVIDENCE, RHODE ISLAND, ASSIGNOR TO LIVERMORE AND KNIGHT COMPANY, OF PROVIDENCE, RHODE ISLAND, A CORPORATION OF RHODE ISLAND

EASEL FOR A POSTER

Application filed July 29, 1929. Serial No. 381,930.

The present invention relates to flexible posters and particularly to the stands or easels for supporting the same in proper position.

5 One object of the invention is to produce a poster stand of very simple, inexpensive construction, light in weight, easily set up and taken down, and which may be taken apart and compactly packed for shipment with the poster.

10 Another object is to insure sufficient tension on the poster to maintain the same in a plane, without the use of springs or the like.

15 Other objects and advantageous features will be more fully described in the detailed description following, in conjunction with the accompanying drawings, and will be particularly pointed out in the appended

20 claims.

In the drawings:

Fig. 1 is a perspective view of the improved easel maintaining a display poster taut;

25 Fig. 2 is a side elevation partly in section, of the parts, the easel being unassembled;

Fig. 3 is a view similar to that of Fig. 2, the easel being assembled;

30 Fig. 4 is a view, partly in section, of the two portions of the easel support; and

Fig. 5 is a view of the easel base piece.

Posters and display advertisements have heretofore been mounted on a solid backing, such as cardboard or the like, or have been mounted on a flexible backing supported by a folding stand or easel. The folding stands or easels have heretofore been cumbersome, difficult to set up properly, and relatively costly, thus increasing the expense

35 of furnishing them to retail stores and other display places, and increasing the possibility of improper setting up and breakage. I have devised a simple, inexpensive easel for a flexible poster consisting of a vertical support rod, which may be sectional, and a sub-

40 substantially horizontal base rod of springy material, a plurality of openings in the support rod being adapted to receive the end of the base rod to obtain the proper spreading

45 of the poster; and the following is a detailed

description of one embodiment constructed in accordance with the principles of my invention.

Referring to the drawings, the flexible poster or display device 10 has a bar 11, 55 preferably of wood, secured to each end thereof. Each bar 11 has a central opening 12 therein to receive one end of the support rod 13 and the base rod 14 therein, as hereinafter described.

60 The support rod 13 is preferably of wood, and is formed of two sections 13a, 13b, having an interlocking pin 15 and socket 16 respectively. The pin should fit tightly into the socket, but if desired, a cross pin 16 65 may be passed through correspondingly aligned openings 16a, 16b, in the pin and socket to firmly join the two sections together. The lower section 13b has a plurality of openings 17 angularly disposed with 70 relation to the lower recess 12, as shown in Fig. 4, in order to impart bending strain to the base rod, and the upper section 13a has a pin 18 adapted to be received in the opening 12 of the upper bar 11. The base 75 rod 14 is of springy, resilient material and has two end pins 19, 20, to be respectively received in the opening 12 of the lower bar 11 and in a selected opening 17.

75 The assembly of the improved easel is as 80 follows:

The two sections 13a, 13b are joined, the end 18 is inserted in the opening 12 of the upper bar, the end 20 of the base rod is inserted in an opening 17 of the lower section, 85 and then a slight bending strain is placed on the base rod and the end 19 is inserted in the opening 12 of the lower bar to maintain the bending strain. The poster 10 is therefore maintained taut by the 90 spring of the base rod. To ship or mail the device, the support rod sections and the base rod are rolled up in the poster, to which the bars 11 are secured, thus forming a light, compact bundle.

95 The improved easel or stand is therefore very inexpensive, is easily set up and taken down, forms a compact, convenient parcel for shipping or mailing, and has no adjustable parts or movable parts to get out of 100

order or to break. While I have described a specific embodiment of my invention, it is obvious that desired changes in the structure or arrangement of the parts may be made, within the scope of the invention as defined in the appended claims.

I claim:

1. A flexible poster device comprising edge bars secured to the upper and lower ends of the poster, central recesses in each bar, a support rod having one end secured in the recess of the upper bar and having an opening in the other end portion, and a resilient base rod having one end secured in the recess of the lower bar and the other end in the opening in said support rod, the opening in said support rod being angularly disposed with respect to the position of said base rod to place the same under bending tension.
- 15 2. A flexible poster device, comprising edge bars secured to the upper and lower ends of the poster, central recesses in each bar, a support rod having one end secured in the recess of the upper bar and having a plurality of longitudinal spaced openings in the other end portion, and a resilient base rod having one end secured in the recess of the lower bar and the other end selectively positioned in one of the openings, the openings in said support rod being angularly disposed with respect to the position of said base rod to place the same under bending tension when in its selected opening.

35 In testimony whereof I affix my signature.

WALTER O. HOLT.
